CARBURETOR

Scott F. Hunt, Detroit, Mich., assignor to Bendix
Aviation Corporation, South Bend, Ind., a cor-
poration of Delaware

Application December 27, 1932, Serial No. 649,071

2 Claims. (Cl. 261—39)

This invention relates to temperature responsive control mechanism for carburetors and has for its principal object the provision of mechanical arrangements for modifying the temperature control in accordance with throttle 5 position.

Internal combustion engines which burn a mixture of liquid fuel and air require a rich mixture, that is a high proportion of fuel to air, when starting. The richness of the mixture must be graded down when the engine begins firing to prevent flooding the engine, but this grading down must be gradual since the engine requires a richer mixture when cold than when 10 at normal operating temperature.

Carburetors for such engines are provided with a throttle for regulating the quantity of mixture and a control valve, usually an air regulating or choke valve, for adjusting the richness of the mixture. It is old in the art to provide 15 temperature responsive devices for regulating the choke valve to grade down the richness of the mixture as a function of engine temperature, such an arrangement being shown in Patent 1,945,191 issued January 30, 1934, to the present applicant.

The present invention improves upon the arrangements of the prior art by interconnecting the choke valve and throttle so as to modify the 20 choke valve setting in accordance with the position of the throttle. The interconnecting means is arranged so that when the throttle is in starting position the choke valve is closed and when the throttle is closed the choke valve is cracked 25 or slightly opened to admit more air than is permitted by the tension in the thermostat. The interconnecting means is also arranged to crack the choke valve at wide open throttle so that an excess of air may be drawn into the 30 engine to clear a flooded condition.

My invention will be best understood from the detailed description and claims which follow, reference being had to the accompanying drawing in which a preferred embodiment is shown 35 by way of example and in which:

Figure 1 discloses one form of the invention in which a pull spring is arranged to add to the tension of the thermostat in the limit positions of the throttle; and

Figure 2 is a fragmentary view, drawn to an enlarged scale, showing the details of the lever by which the pull spring of Figure 1 is connected to the choke valve.

Referring now to the drawing in more detail, 40 in Figure 1 I have shown a plain tube down

draft carburetor 10 having a choke valve 12 located in the inlet horn and a throttle valve 16 for controlling the mixture chamber 17. The particular type of carburetor may be varied within the teachings of the invention. The choke valve 12 is preferably of the unbalanced type arranged to be opened by difference in pressure on its anterior and posterior faces, and the throttle is preferably the butterfly type shown. 5

The choke valve 12 is mounted upon a shaft 18 to which an operating lever 60 is fixed, and the throttle is mounted upon a shaft 22 to which an operating lever 24 is secured. A rod 62 is pivoted to one end of lever 60 and the free end of the rod is pivotally connected 10 to the arm 64 of thermostat 66, which, when cold, is tensioned to hold valve 12 closed.

A lever 76 is loosely mounted on the choke valve shaft 18. The shaft carries a pin 78 which is arranged to strike against a pin 80 carried 20 by lever 76 to limit the movement of the lever with respect to the shaft. A pull spring 82 is connected between the free end of lever 76 and the throttle lever 24. When the throttle is set in starting position, spring 82 has zero tension 25 and thermostat 66 is tensioned sufficiently to hold the choke valve closed against the vacuum produced in the mixing chamber of the carburetor at cranking speed. When the throttle is moved to its fully closed position, spring 82 30 is tensioned to rotate the lever 76 clockwise on shaft 18. Pin 80 strikes against shaft pin 78 and the shaft is moved to crack the choke valve so that sufficient air will be admitted to prevent flooding of the engine. The movement of lever 35 76 is limited by an adjustable stop 84 to regulate the amount of opening of the choke by spring 82. When the throttle is moved to wide open position spring 82 is tensioned to crack the choke valve, and a flooded condition can be 40 remedied. When the choke valve is opened by air pressure pin 78 moves away from pin 80 and spring 82 no longer influences the movements of the choke valve.

The details of the arrangement shown and 45 described are by way of example only, and may be varied to meet specific conditions within the teachings of the invention.

I claim:

1. In a control mechanism for a carburetor 50 having a choke valve and a throttle, the combination of a thermostat for governing the degree of opening of the choke valve as a function of temperature, means connecting the valve and throttle for partially opening the valve when 55

the throttle is fully closed, and means for limiting the degree of opening of the valve by said means.

2. In a control mechanism for an internal combustion engine carburetor having a choke valve and a throttle, a thermostat tensioned to

set the choke valve to produce a starting mixture for the engine, and means controlled by the throttle for decreasing said tension to set the choke valve to produce an idling mixture for the engine.

SCOTT F. HUNT.
